United States Patent Office.

SAMUEL M. KING, OF LANCASTER, PENNSYLVANIA.

Letters Patent No. 96,444, dated November 2, 1869.

IMPROVEMENT IN SHINGLE-MACHINE.

The Schedule referred to in these Letters Patent and making part of the same

To all whom it may concern:

Be it known that I, SAMUEL M. KING, of the city of Lancaster, in the State of Pennsylvania, have made new and useful Improvements on Machines for Cutting and Planing Shingles; and I do hereby declare that the following is a full, clear, and exact description of the construction and operation of the same, reference being had to the accompanying drawings, making a part of this specification, in which—

Figure 1 is a perspective view of the machine, with my improvements in place.

Figure 2 is a side elevation.

Figures 3, 4, and 5, detached parts, shown separately.

The nature of my invention consists in the use of two separate beds, one adjusted by set-screws and the other on elliptic springs, both held in a box or side-pieces, and operating in unison, furnished with knives, so as to split off and plane a shingle on one side in the forward motion, while the bolt and severed slice remain stationary, which, in the back motion, drops on to the bevelled or finishing-bed, where the upper surface is planed and tapered to finish the shingle, by means of a crank, actuating the boxed plates back and forth under certain fixed portions of the machine.

To enable others skilled in the art to make and use my invention, I will now describe its construction and operation.

Any suitable frame-work, provided with central uprights U, spur-wheel, crank, and connecting-rod, to give a back and forward motion to the beds B and M, between the side-pieces C, which are made to slide in fixed grooved rails A A', horizontal or inclined in their position, and supported by uprights, in the ordinary manner, and as shown.

The planing and riving bed B is supported upon a pair of elliptic springs, and made adjustable, centrally, by a screw-bolt, allowing the plate to move up and down between the side-pieces or box-ends C C'.

This plate B is cut out with projecting ends, across which a planing-knife, K, fig. 5, is set and adjusted with the bed, the springs underneath keeping the planer up to its work, while at the same time they yield when grained pieces offer too much wood, and secures the machine against breaking by too great a strain.

Over the planing-knife K is the riving-knife I, secured to the top of the side or box-pieces C C, projecting a little beyond the planer K'.

This riving-knife I wedges downward, resisted by the action of the knife K, on the spring-bed B.

The central posts U U rise above the beds, supporting on the one side a drop or head-block, II, moving up and down in grooved end-pieces, and notched

out in the lower corners, to allow it to drop on the bed.

A plate, F, connects the posts U U on the other or forward side.

To this plate F the spring-tongue or holder G is bolted.

This holder has an open space for the riving-knife to pass through between the sides, which are bent forward and united across, so as to suspend this cross-piece above the planer K and under the riving-knife I, in order to hold the slice riven off and being planed, without interfering with the action of the knives, passing the one under and the other over it, in the forward motion of the boxed beds M B, the bed M being adjusted by set-screws, to give it the desired slope or taper for the shingle, and is in close connection to the spring-bed B.

Between them are the lifters P, for raising the spring-roller O N on the sides of the raised portion of the box-pieces C C, and also the wedged-pieces z on the top of the same, to raise the cross-head or drop-plate H, to allow the passage of the riving-knife.

The stationary knife R is bolted across the machine, on to the top of the outer guide-rails A A, and not only planes the upper surface of the shingle, but gives it the desired tapering cut, held by the spring-roller N O, and supported by the carrier Q, in their fixed position, through the adjustment and back-action of the bed M.

The operation may be briefly stated:

Supposing the beds back their full stroke, the bolt of wood S cut to length, laid upon the planing or spring-bed B, butting against the head-block or plate H. In this position the riving-knife and planer I K are in the rear of the bolt, which latter cannot move forward.

The action of the crank and connecting-rod draws the beds B M forward under the bolt, riving off a slice and planing it from end to end, the slice riven off and planed being held in place by the spring-tongue G during the operation. The back-action of the beds or combined box would now push, or rather carry the bolt back. This the attendant prevents, by placing his hand on the bolt, allowing the severed and partially planed piece to drop down upon the adjusted bed-plate M, where it is subjected to the stationary knife R and spring-roller N O, where the upper surface is planed off and the proper taper given to finish the shingle by the time the beds are again drawn forward to rive and plane another piece, as the finished shingle is released and drops to the ground, thus each revolution of the crank-wheel finishes a shingle. The number cut in a minute is governed by the speed of the machine.

I am aware that automatic dogs might be attached, to hold and govern the bolt, but would be less efficient than the slight attention required given by hand.

I am aware that various devices are employed and patented for cutting and sawing shingles; but I am not aware of a machine in which the bolt and riven piece are held in place while being riven and planed on the under side, and the piece dropped from one bed upon the other, and there bevelled and planed on the upper side, by the back and forward motion of the separate beds moving in unison to perform these functions, in combination with the stationary appliances described. Therefore, I do not claim the planing, riving, and tapering-knives, nor the roller and straight and tapering-faced beds or plates, separately considered; nor do I claim combining, in a

single reciprocating plate, a straight face and a tapering face, with an offset between them, and a moving froe, *i. e.*, having motion in itself.

What I claim, and desire to secure by Letters Patent, is—

The arrangement of a shingle-machine, provided with two beds M B, in a line with each other, made separately adjustable between the side rails C, when the bed B is supported on springs E, or their equivalent, and carries the planer I and riving knife K, as shown, together with the spring-tongue or holder G suspended, and all operating jointly, substantially in the manner and for the purpose specified.

SAM'L. M. KING.
